UNITED STATES PATENT OFFICE.

WILLIAM A. WATSON, OF MALDEN, MASSACHUSETTS, ASSIGNOR TO NATIONAL PIANO COMPANY, OF BOSTON, MASSACHUSETTS, A CORPORATION OF MAINE.

AUTOMATIC LOCKING DEVICE FOR TRACKER MECHANISM.

1,112,242.

Specification of Letters Patent.

Patented Sept. 29, 1914.

Application filed May 31, 1913. Serial No. 771,034.

To all whom it may concern:

Be it known that I, WILLIAM A. WATSON, a citizen of the United States, residing at Malden, in the county of Middlesex and 5 State of Massachusetts, have invented certain new and useful Improvements in Automatic Locking Devices for Tracker Mechanism, of which the following is a specification.

10 This invention relates to so-called automatic musical instruments, and refers particularly to the note sheet mechanism thereof.

15 For various reasons, which are well known, relative lateral displacement frequently occurs between the note sheet and the tracker bar, so that the perforations in the sheet do not accurately register with the apertures in the tracker bar.

20 Most pieces of music run through, from roll to roll in the spool box, correctly, if started right. As a matter of fact, however, it is not often that the sheet is started really accurately.

25 One of the objects of the present invention is to provide means whereby the correctness of relationship of the note sheet and tracker bar can be secured once, and then the sheet left to itself, because it will 30 then usually run through straight.

Another object of the invention is to provide means whereby the performer can, at will, bring the note sheet and tracker bar to positive alinement, or absolutely correct 35 relative position, without requiring skill to effect the proper manipulation.

Several attempts have been made to maintain a correct registration between the note sheet and tracker bar, and one of such attempts in particular has resulted in a structure which causes a constant shifting of the 40 music sheet, or of the tracker bar. This is undesirable because of the wear of the sheet. When there is a constant lateral shifting, 45 a series of small lines or grooves are formed in the back of the note sheet, and repeated use of the sheet results in these lines crossing each other, so as to eventually dislodge fine particles or fibers which tend to clog 50 the mechanism.

Another object of the present invention is to provide an improved mechanism whereby the proper relationship between the music sheet and the tracker bar once 5 secured, is locked, so that the number of

crossing lines in the back of the paper due to the repeated use of the sheet, is reduced to the minimum. The present improved mechanism, however, provides means whereby the performer can, at any time, bring the parts back to proper relationship, if they do get out of that relationship after starting. 60

The mechanism which I have invented, never inaugurates the action of the shifting 65 or correcting devices, but merely indicates to the performer that he is to do something to cause the mechanism to restore the correct relationship. In the embodiment of the invention illustrated, a button or valve 70 is actuated by the performer in order to cause the mechanism to effect a shifting of the tracker bar or the note sheet, to correct relationship. For convenience of description, reference will hereinafter be 75 made to shifting the tracker bar, it being assumed that the spool box is mounted in stationary position. Obviously, however, the tracker bar might be secured in a stationary position and the spool box mounted 80 so as to be shifted.

Of the accompanying drawings,—Figure 1 is a front elevation, partly broken out or in section, of so much of an instrument of the character described, as is necessary 85 to illustrate the invention. Fig. 2 is a view similar to the upper portion of Fig. 1, but showing the parts in the positions which they occupy when the proper relationship exists between the note sheet and 90 the tracker bar. Fig. 3 is a perspective diagrammatic view, illustrating some of the conduit connections. Fig. 4 is a plan view, partly broken out or in section. Figs. 5, 95 6, and 7, represent, respectively, sections on line 5—5, 6—6, and 7—7 of Fig. 1, Fig. 7 being on a somewhat larger scale than the other figures. Fig. 8 is a view similar to Fig. 1, but illustrating another embodiment 100 of the invention. Fig. 9 represents a section on line 9—9 of Fig. 8, and Fig. 10 represents a section on line 10—10 of Fig. 9.

Similar reference characters indicate similar parts in all of the views. 105

Referring first, to Figs. 1 to 7, inclusive, the spool box 12, and the tracker bar 13, are of any well known or preferred form of construction. The studs 14 of the tracker bar are mounted in the spool box so that 110

there can be a movement of one relatively to the other in a direction transverse of the note sheet 15, carried by the usual rolls 16, 17. A link 18 connects one of the studs 14 with a lever 19 pivoted at 20, to a bracket 21, projecting from the side of the spool box, the construction being such that when the lever 19 is shifted from the position shown in Fig. 1 to that shown in Fig. 2, or vice versa, the lateral position of the tracker bar relatively to the spool box will be changed. If the tracker bar were mounted in stationary position, and the spool box free to be shifted on the studs 14, then movement of the lever 19 would effect the same result as above explained.

My improved attachment includes two frame members, 22, 22, suitably supported relatively to the spool box 12. In the construction illustrated, it being assumed that the spool box is stationary, the support for the frame members 22 is provided by an upper bracket 23 and two lower strips 27, (Figs. 1, 2, and 7) projecting laterally from the spool box. Between the two frame members 22 is an upper block 24, and a lower block 25, and a cross strip 26, the latter being near the lower ends of the frame members 22.

Connected to the outer faces of the frame members 22, by means of hinge strips 28, are two pneumatics 29, 30, which are herein-after referred to as the shifting pneumatics, since they constitute the motor or motors which effect the proper registration of the note sheet and tracker bar, when permitted to do so by an act of the performer. The two shifting pneumatics are connected by a link 31, so that when one collapses, the other must expand, and vice versa. A link 32 connects one of these pneumatics with the lever 19, so that the motors of these two pneumatics will operate through the lever 19 to shift the tracker bar in the direction of its length, transverse of the note sheet.

Secured to the inner faces of the lower portions of the frame members 22, are two smaller pneumatics 33, 34, which, for convenience of description I shall hereinafter refer to as the controlling pneumatics, because they act to lock and release the shifting pneumatics. Each controlling pneumatic 33, 34, has a bracket 35 which engages the upper end of a lever 36 pivoted at 37 to the cross strip 26, springs 38 being connected to the levers 36, as shown in Fig. 1, so as to act to normally hold the levers 36 with their upper ends in contact with the outer abutments of the brackets 35. Said outer abutments are spaced at some distance from the inner ends of the brackets, so as to permit of some play of the levers 36 relatively to the pneumatics 33, 34, for the purpose hereinafter explained. This play or lost motion is illustrated by full and

dotted lines in Fig. 2. Each lever 36 has an eye 39 at its lower end (Fig. 7), through which an arm 40 passes, the two arms 40 being pivotally connected at 41 to ears 42 of the shifting pneumatics 29, 30. The eyes 39 are but slightly larger than the arms or rods 40, so that the levers 36 will lock the arms 40, and consequently, the shifting pneumatics, excepting when the portion of either lever which has the eye 39 is substantially at a right angle to the arm 40, passing through said eye. In other words, when these two members are at a right angle to each other, the rod 40 can slip through the eye 39, but as soon as the lever has 80 swung away from said right-angled relationship, it will lock the arm 40. In Fig. 2 the dotted line representation of one of the levers 36 represents the position of said lever when it is not locking the arm 40. When the levers 36 occupy the full line position, both arms 40 are locked.

The tracker bar 13 (see Figs. 1, 2, and 3) is provided with two ports *a*, *b*, which are spaced apart a distance slightly greater than 90 the regulation width of the note sheet 15, so that at no time can the sheet obstruct both of the ports, and so that when the proper relationship exists between the note sheet and tracker bar, both ports *a*, *b*, will be 95 open, as shown in Fig. 2.

To facilitate an understanding of the operation, duplicate reference letters with different numeral exponents are used to designate those conduits and chambers in 100 which a change of air pressure occurs, when the mechanism is in operation. Pipes *a'*, *b'*, lead from the ports *a*, *b*, and since the ports *a*, *b*, are normally open to the atmosphere when the parts are in the position shown in Fig. 2, there is normally an equality of atmospheric pressure in both of the pipes *a'*, *b'*, said two pipes *a'*, *b'*, lead to chambers *a*², *b*², respectively, (see Figs. 1, 2 and 7) in the block 25. Diaphragms 43 110 cover the chambers *a*², *b*². The space in the block above the diaphragms 43 is constantly subjected to air tension, or what is commonly in this art, termed a "vacuum", by means of a pipe 44 connected with the usual 115 air-exhausting mechanism of the instrument. The chamber above the diaphragms 43 is indicated at V in the drawings, this letter being employed to indicate that it is a 120 so-called "vacuum" chamber.

In the block 25 above the chamber V, are two vertical apertures *a*³, *b*³, and valves *a*⁴, *b*⁴, have their stems mounted in the apertures *a*³, *b*³, the valves proper being adapted to close the upper ends of the apertures, the lower ends of the stems of the valves bearing upon disks carried by the diaphragms 43. A port *a*⁵, (Figs. 1, 2, and 6) connects the aperture *a*³, with the controlling pneumatic 33. A similar port *b*⁵ (Fig. 6) connects the 130

aperture b^3 with the controlling pneumatic 34. The chambers a^2 , b^2 , are connected with the chamber V by small vent or "bleeding" ports a^6 , b^6 .

5 Referring to Fig. 1, 45 indicates a rail, or a key-bed, just below the keys 46 of the musical instrument. Supported by the rail 45, in convenient juxtaposition to the keys 46, are two push-buttons 47, each having a stem 10 48 projecting downwardly through the rail. The two push-buttons are adapted to be actuated by the performer, as hereinafter described. The stems bear upon, so as to open, two valves c , d , the ports controlled 15 by said valves being connected respectively by means of pipes c' , d' , with chambers c^2 , d^2 , in the upper block 24, (see Figs. 1, 2, 3 and 7). The two chambers c^2 , d^2 , are covered by diaphragms 49, the chamber in the 20 block 24 above said diaphragms being connected with the vacuum pipe 44, and being therefore indicated by the same reference character V as is employed for the corresponding chamber in the lower block 25. 25 The block 24, is provided with vertical apertures c^3 , d^3 , communicating with the chamber V, the stems of the two valves c^4 , d^4 , being mounted in said apertures, the lower ends 30 of said stems being adapted to bear upon disks secured to the diaphragms 49, the heads of the stems, or the valves proper, being adapted to close the upper ends of the apertures c^3 , d^3 . The apertures c^3 , d^3 , are connected, respectively, by ports c^5 , d^5 , with the shifting pneumatics 29, 30, (Figs. 1 and 2, and dotted lines in Fig. 4).

So long as the relationship between the note sheet and tracker bar remains as indicated in Fig. 2, the registration being then proper, no occasion arises for the operation of the mechanism which I have described. If the sheet, however, should be started wrong, or if for any reason, one of the ports a or b should become covered by 45 the edge of the note sheet, then the mechanism is put into condition to operate to return the parts to proper relationship as soon as the performer presses one of the push buttons 47. Supposing the relationship has 50 become as indicated in Fig. 1, thus covering the port a . This shuts off atmospheric pressure in pipe a' and chamber a^2 (Fig. 7). Prior to this shutting off, the diaphragm 43 or chamber a^2 , will have occupied the same 55 upper position as that occupied by the diaphragm over chamber b^2 , owing to the "vacuum" in chamber V. Air pressure being shut off in diaphragm a^2 , the diaphragm above it falls to the position shown in Fig. 60 7, this action being aided by the small port a^6 , which transmits the "vacuum" to chamber a^2 . Valve a^4 closes the upper end of aperture a^5 , and the result of suction in aperture a^5 is transmitted through port a^5 55 (Figs. 1, 2 and 6), so as to reduce the con-

trolling pneumatic 33, the latter collapsing, as indicated in Fig. 1. The bracket 35 of the pneumatic 33 acts upon the left-hand lever 36 (Fig. 1) so that its eye 39 will no longer lock the rod 40. The mechanism is 70 therefore put into condition to operate to reattain the proper relationship of the note sheet and tracker bar by the performer depressing the left-hand button 47 (Fig. 1). While the performer might be able to notice that the note sheet and tracker bar are in 75 improper relationship, by the fact that one edge of the paper sheet is covering the port a , I prefer to provide an indicator which will emphasize the fact. Said indicator comprises a pointer 52 pivotally connected at 53 to a bracket 54 secured to one end of the tracker bar 13. A plate 57, which may bear the words "Left" and "Right," is attached to a portion of the spool box 12, said 80 plate having a zero point 56 and a guard bar 57 which extends in front of the tip of the pointer to protect the same. The indicator pointer 52 is provided with a lug or projection 58, adapted to be engaged by the 85 edge of the note sheet 15.

The indicator pointer is so hung that gravity will cause it to follow lateral shifting of the note sheet to an extent that would permit the tip of the pointer to move practically over to the word "Right", if the sheet should shift so as to cover the port b , said pointer being pushed over toward the word "Left" when the note sheet covers the port a . If now the performer, noticing by 100 means of the indicator, or otherwise, that the port a is covered, depresses the left-hand button 47, air will be admitted to the pipe c' . At this point it is to be understood that the "vacuum" or suction exists 105 in the chamber V of block 24 (Fig. 7), and that this suction is normally transmitted also to both of the chambers c^2 , d^2 , so long as neither valve c or d has been opened, and, consequently, the valves c^4 , d^4 , would be 110 normally in the position shown in Fig. 7. As soon as air has been admitted, however, to pipe c' , by the act of the performer depressing the left-hand button 47, the "vacuum" in the chamber V, above chamber c^2 , 115 results in the diaphragm 49 rising and lifting the valve c^4 , and opening the aperture c^3 to the atmosphere, the disk upon the diaphragm 49 closing the lower end of said aperture. This admits atmospheric air 120 through port c^5 to the pneumatic 29. Since the "vacuum" or suction has not been cut off from the other shifting pneumatic 30, the two shifting pneumatics move toward the left (being connected by the link 31) 125 so that, through the link 32, the lever 19 is actuated to exert a pull upon the tracker bar so as to again expose the port a which had been covered, thus restoring the relationship of the note sheet and tracker bar, 130

as shown in Fig. 2. The reason why the shifting pneumatics can be so moved as thus described, is that the parts when in the position shown in Fig. 1, cause the left-hand lever 36 to release the left-hand lock arm 40. The right-hand arm 40 can be readily moved through the eye of the right-hand lever 36, because the upper end of that lever can be swung to the dotted line position shown in Fig. 2. In other words, either arm 40 can be pushed through the eye of its lever 36, because of the lost motion connections provided between the upper ends of the two levers 36 and the two brackets 35, the springs 38 immediately restoring the levers 36 to locking position so that neither arm 40 can be pulled through the eye. Either arm 40 can be pushed through the eye of its lever 36, but cannot be pulled, and therefore the two shifting pneumatics 29, 30, although movable in unison toward the right or the left, are normally locked and cannot be moved in either direction until one or the other of the two levers 36 has been shifted to unlock its arm 40, by the collapsing of the controlling pneumatic 33 or 34. These two controlling pneumatics 33, 34, are put in condition to be collapsed by the covering of the port *a*, or the port *b*, by the note sheet.

Most of the foregoing description of operation relates to what results from the covering of port *a*. Obviously, the covering of port *b*, would result in similar operations, but through the pipe *b'*, chamber *b*², aperture *b*³, valve *b*⁴ and port *b*⁵ to controlling pneumatic 34, so that if the port *b* should be covered by the note sheet, the result would be to actuate the lever 19 in the opposite direction to that hereinbefore described, provided the performer depresses the right-hand button 47, so as to admit air to pipe *d'*, and the chamber *d*², so that the lifting of the diaphragm 49 over chamber *d*², will lift the valve *d*⁴, so as to open the aperture *d*³, to atmospheric pressure, and then permit the latter to gain access to the shifting pneumatic 30, suction still then existing in pneumatic 29, the two pneumatics 29, 30, then swinging to the right and, through link 32 and lever 19, pushing the tracker bar toward the right so as to again uncover port *b*, and restore the proper relationship of the note sheet and tracker bar.

Figs. 8, 9, and 10 illustrate another embodiment of my invention, whereby a single push-button, or equivalent device, under the control of the performer, may be employed for causing the motor to act in the proper direction, instead of the right and left-hand buttons illustrated in Fig. 1. In Figs. 8 and 9, the reference characters which are the same as in the other figures, designate the same elements as in the other figures. The block 24, however, is formed or

provided with a lower extension 60, in which are formed two ports *c*⁷, *d*⁷, extending from one side of said extension up to points to communicate with the chambers *c*², *d*², respectively. A switch piece 61 is pivoted at 62 to the side of the extension 60, and is formed with a passageway 63 through it, the ends of said passageway being adapted to register alternately with the lower ends of the two ports *c*⁷, *d*⁷. A push-button and valve structure *e* which may be similar to either of the push-buttons 47 and valves *c*, *d*, in Fig. 1, controls the lower end of the pipe *e'*, the other end of which communicates with the passage 63 in the switch block 61, so that when said switch block is oscillated, as hereinafter described, air may be admitted to one or the other of the two chambers *c*², *d*², according to the position of the switch. Said switch is provided with ears 64, 65, at its opposite ends, said ears having depending rods 66, 67, provided with adjustable collars 68, the lower faces of which are engaged by lever arms 69, 70, carried respectively by the controlling pneumatics 33, 34.

The operation of the mechanism illustrated in Figs. 8, 9, and 10, is as follows: If the note sheet 15 shifts one way or the other so as to cover one of the ports *a* or *b*, the result of action of the pneumatic 33, or 34, as hereinbefore described, in connection with Figs. 1, 2, and 7, will be to cause the lever arm of the controlling pneumatic which is collapsed, to lift the depending rod which is engaged with that lever arm, so as to shift the switch 60 (provided said switch is not already in proper position), so that when the operator then depresses the push-button *e*, air will be admitted to the proper chamber *c*² or *d*², to cause the motor pneumatics 29, 30, to operate in the same manner hereinbefore described in connection with Figs. 1, 2, and 7. Preferably, an indicator pointer will be used in connection with the embodiment of the invention illustrated in Figs. 8, 9, and 10, similar to that already described in connection with the other figures, so that the performer will more readily perceive the fact that a readjustment of the relationship of the note sheet and tracker bar is to be effected, the performer then simply actuating the push-button *e*. If the proper controlling pneumatic 33, or 34, is collapsed, the switch 61 is of course in proper position so that the depression of the push-button *e* will cause the motor to act in the proper direction. If the other port of the tracker bar becomes closed, the result will be, of course, to automatically cause the other one of the two controlling pneumatics to be collapsed, and this will oscillate the switch so that communication will be established from the pipe *e'* to the proper port *c*⁷ or *d*⁷, so that the depre-

sion of the push-button *e* will result in the motor pneumatics 29, 30, operating to restore correct registration of the note sheet and tracker bar.

5 In both forms illustrated, the pneumatics 29, 30, together, constitute a motor actuating the lever 19 to restore registration of the note sheet and tracker bar, and the pneumatics 33, 34, constitute controlling mechanism for the motor pneumatics 29, 30. The controlling mechanism is governed by the note sheet, and when the position of the note sheet causes the controlling mechanism to release the motor, the performer can then 15 set the motor in operation.

I claim:

1. Mechanism of the character described, comprising a tracker bar and a note-sheet support, one of which is shiftable relatively 20 to the other, a motor for effecting such shifting, controlling mechanism governed by the note sheet for placing the motor in condition to act, and means under the control of the performer for causing the motor to act when placed in condition to act by said controlling mechanism.

2. Mechanism of the character described, comprising a tracker bar and a note-sheet support, one of which is shiftable relatively 30 to the other, a motor for effecting such shifting, controlling mechanism governed by the note sheet for placing the motor in condition to act, an indicator to show the proper direction of shifting to secure registration 35 of the tracker bar and note sheet, and means under the selective control of the performer for causing the motor to act in the selected direction when placed in condition to act by said controlling mechanism.

40 3. Mechanism of the character described, comprising a tracker bar and a note-sheet support, one of which is shiftable relatively to the other, a normally locked motor for effecting such shifting, lock-releasing devices 45 governed by the note sheet, and manually controlled devices to cause the motor to act when unlocked.

4. Mechanism of the character described, comprising a tracker bar and note-sheet support, one of which is shiftable relatively 50 to the other, a tracker bar having ports spaced relatively to each other a distance greater than the width of the note sheet employed in connection with the tracker 55 bar, a motor for restoring registration of the note sheet and tracker bar, controlling mechanism for placing the motor in condition to act, said mechanism being governed by which one of the ports in the tracker 60 bar may be covered by the note sheet, and means under the control of the performer for causing the motor to act in a proper direction.

5. Mechanism of the character described, 65 comprising a tracker bar and a note-sheet

support, one of which is shiftable relatively to the other, a motor comprising a pair of connected pneumatics, connections between said pneumatics to restore registration between the note sheet and tracker bar, controlling mechanism governed by the note sheet for placing the motor in condition to act, and means under the control of the performer for causing the motor to act when placed in condition to act by said controlling mechanism.

6. Mechanism of the character described, comprising a tracker bar and a note-sheet support, one of which is shiftable relatively to the other, a motor for effecting such shifting, a pair of independent controlling pneumatics for the motor, connections for effecting the collapsing of either one of the controlling pneumatics according to the relative position of the note sheet and tracker bar, and means under the control of the performer for causing the motor to act.

7. Mechanism of the character described, comprising a tracker bar and a note-sheet support, one of which is shiftable relatively 80 to the other, a motor comprising a pair of connected pneumatics, connections with said motor for effecting relative shifting of the note sheet and tracker bar, said motor pneumatics having arms, a pair of controlling 85 pneumatics, levers adapted to be actuated by the controlling pneumatics, said levers having means for locking the arms of the motor pneumatics when in one position, and means under the control of the performer 90 for causing the motor to act when unlocked.

8. Mechanism of the character described, comprising a tracker bar and a note-sheet support, one of which is shiftable relatively 95 to the other, a motor comprising a pair of connected pneumatics, connections with said motor for effecting relative shifting of the note sheet and tracker bar, said motor pneumatics having arms, a pair of controlling pneumatics, levers adapted to be actuated by 100 the controlling pneumatics, said levers having means for locking the arms of the motor pneumatics when in one position, the levers having eyes through which the arms of the motor pneumatics pass, said eyes being 110 adapted to bind the arms, and means under the control of the performer for causing the motor to act when unlocked.

9. Mechanism of the character described, comprising a tracker bar and a note-sheet 120 support, one of which is shiftable relatively to the other, a motor comprising a pair of connected pneumatics, connections with said motor for effecting relative shifting of the note sheet and tracker bar, said motor pneumatics having arms, a pair of controlling 125 pneumatics, levers adapted to be actuated by the controlling pneumatics, said levers having means for locking the arms of the motor pneumatics when in one position, the levers 130

- having eyes through which the arms of the motor pneumatics pass, said eyes being adapted to bind the arms, lost motion connections being provided between the levers and controlling pneumatics, and means under the control of the performer for causing the motor to act when unlocked.
10. Mechanism of the character described, comprising a tracker bar and a note-sheet support, one of which is shiftable relatively to the other, a frame having upper and lower chambered blocks, a pair of motor pneumatics having ports connected with the chambers of the upper block, a pair of controlling pneumatics having ports communicating with the chambers of the lower block, connections with the power pneumatics to effect relative shifting of the tracker bar and note sheet, connections for governing the 20 action of the controlling pneumatics by the relative positions of the tracker bar and note sheet, and means under the control of the

performer for causing the motor pneumatics to act.

11. Mechanism of the character described, 25 comprising a tracker bar and a note-sheet support, one of which is shiftable relatively to the other, a motor for effecting such shifting, controlling mechanism for the motor governed by the note sheet, an indicator 30 pointer pivotally supported by the tracker bar and adapted to bear against one edge of the note sheet to indicate changes of relative positions of the note sheet and tracker bar, and means under the selective control of 35 the performer for causing the motor to act in the selected direction.

In testimony whereof I have affixed my signature, in presence of two witnesses.

WILLIAM A. WATSON.
